Primary Examiner — Cynthia Underwood(74) *Attorney, Agent, or Firm* — Novoclaims Patent Services, LLC; Mei Lin Wong**CLAIM**

The ornamental design for a protective casing for PDA, Tablet PC, IPAD and the like, as shown and described.

DESCRIPTION

FIG. 1 is a front perspective view of a protective casing for PDA, Tablet PC, IPAD and the like showing my new design. FIG. 2 is a front view thereof.

FIG. 3 rear view thereof.

FIG. 4 is a left end view thereof.

FIG. 5 is a right end view thereof.

FIG. 6 is a top view thereof.

FIG. 7 is a bottom view thereof.

FIG. 8 is a rear perspective view thereof; and,

FIG. 9 is a front perspective view showing a standing position thereof.
